UNITED STATES PATENT OFFICE.

EDWARD C. RICHARD AND HARGRAVES GILL, OF WESTBORO, MASSACHUSETTS, AS-SIGNORS TO WESTBORO WEAVING COMPANY, OF NEW YORK, N. Y., A CORPORATION OF NEW YORK.

SHUTTLE.

Application filed August 27, 1924. Serial No. 734,366.

This invention relates to improvements in shuttles and, more particularly, to shuttles used for weaving tape and other narrow fabrics, and being an improvement upon the shuttle shown in our pending application for patent bearing Serial Number 672,472, filed November 3, 1923; Patent No. 1,599,287.

The object of this invention is, more particularly, to secure a more effective take-up 10 device and a suitable tension-device to co-operate with the same.

With such objects in view, our invention consists in the construction and combination of parts as hereinafter described and 15 claimed.

In the accompanying drawings,

Fig. 1 is a side elevation of our device; Fig. 2 is a vertical section thereof on the line 2—2 of Fig. 1;

Fig. 3 is a horizontal section thereof on the line 3—3 of Fig. 1;

Fig. 4 is a side elevation of the tensioning and take-up means;

Fig. 5 is a vertical section on the line 5—5 25 of Fig. 4;

Figs. 6, 7, 8 and 9 show in detail the parts which serve as the mountings for the several members of said tensioning and take-up means.

Referring to the accompanying drawings 30 in detail, the base-piece is shown at 6, being concave on one side, as shown at 7, Fig. 2, and convex on the other side, upon which there is a toothed-rack 8, as appears in Figs. 1 and 2. The surmounting lenticular plate is shown at 9; and the two sides of the arch rising from plate 9 are shown at 12 and 13, the latter being hinged to the plate 9 and 35 13' and the former being split at 17, with a notched-latching-pin 16 on the upper half engaged by a spring-pin 15 on the lower half.

A lenticular plate above the bobbin is 40 shown at 49 in Figs. 1, 2, 3 and 9. In the present case, the plate 49 extends through the arch member 13 and is attached to the bottom of the upper half by screws, as at 13^a and to the lower half of arch member 13 by bracket 13^b and screws 13^c; while the 45 opposite end of the plate 49 is secured to the bottom of the upper half of arch member 12 by the aforesaid said latch-pin 16.

The bobbin 14 stands between the two plates 9 and 49, having a socket which fits

over a short stud on the plate 9 and is secured thereto by an internal spring-latch 18.

In our present invention the tensioning and take-up apparatus is mounted on the upper lenticular plate 49 by means of a bridge-plate 50, shown separately in Fig. 8, 60 which is of an inverted V form, with its respective ends secured to the short bent-up tabs 51 and 52 on the said plate 49 (see Fig. 9). Thus the bridge-plate, with the mechanism thereon, can be readily applied to or 65 removed from the shuttle. As clearly shown in Figs. 7 and 8, incisions are made in said bridge-plate 50 to define a section *a*, which is bent up into a horizontal position to serve 70 as a support for an angle lever 60 pivotally arranged thereon by means of the pin 53' fitting into aperture 53 of said plate. Said plate 50 is also provided with an aperture 54 through which the thread T passes upwardly from the bobbin 14. A tension-spring 61 is secured at one end to a lug 55 75 bent up from the bridge-plate 50 and at its other end to the shorter arm of the lever 60. This spring 61 tends to throw the longer arm of lever 60 outward against a plate 56 80 that rises up from section *a* on one edge of the thread-hole 54 and is bent over the lever 60, with a hole 57 in the overlapping part. Thus, as the thread T emerges upward from hole 54, it passes between plate 56 and the 85 lever 60 before it emerges from the hole 57 in the overlapping part of plate 56. This imposes a drag or tension on the thread according to the tension given to the spring 61.

Rigidly secured to the other edge of said 90 bridge-plate 50, opposite said tensioning device just described, is a bracket B, (see Fig. 6), said bracket having two parallel up-standing ears, the lower alined apertures therein supporting a stub shaft 70 carrying 95 a pinion 74 and adapted to mesh with a toothed sector 72 pivotally connected to the longer ear of said bracket B, and operated by a spring 73, (see Fig. 1). Thereby the said shaft 70 cannot be turned from its normal position without causing the pinion 74 to rotate sector 72 and exert tension on the spring 73. Projecting from the shaft 70, at substantially right-angles thereto, is an arm 71 in which are formed three loops 1, 2 and 100 3 (see Figs. 1, 3, 4 and 5). Under the force of spring 73, this arm 71 tends to occupy the position shown in Fig. 1, lying on the 105

bridge-plate 50, and cannot be turned from that position without stressing the spring. This position may be termed the normal one. There is also a rigidly fixed upright arm 75 (see Figs. 1 and 4) in which there are also loops, two in number, similar to and in the same vertical plane as the loops 1, 2 and 3 of arm 71, when the latter assumes a vertical position.

- 10 The thread T, after emerging under tension, from the hole 57, as above described, passes first through loop 3 on arm 71, then through the lower loop on the fixed arm 75, then through loop 2 on arm 71, then through 15 the upper loop on arm 75, and finally through the loop 1 on arm 71, from which it then leaves the shuttle through the eyelet 20 at the top of the arm. This arrangement provides a spring take-up for the 20 thread of large range or capacity, since the amount taken up is multiplied by each set of loops. If the tension on the thread is sufficient to draw the arm 71 from its normal position shown in Fig. 1 up to a vertical 25 position, the loops 1, 2, 3 of arm 71 will be in line with and in alternation with the loops on fixed arm 75 and the thread will go directly up from hole 57 to the outlet hole in eyelet 20 without any slack. On the 30 other hand, if there is sufficient slack in the thread, it will pass back and forth between the consecutive sets of loops on arms 71 and 75 and assume the zig-zag route shown in Fig. 1. As compared with our former 35 arrangement, the present one affords an increased take-up capacity and also has an adequate tensioning capacity at the lever 60, while it is simpler, more compact and cheaper to manufacture.
- 40 It will be evident that modifications may be made in the structure and arrangement of the parts without departing from the scope of our invention. Without limiting ourselves to the exact construction shown 45 and described, what we claim is:
1. A shuttle having a tensioning device and also a take-up device comprising an arm having a plurality of thread-engaging loops, a shaft on which said arm is mounted, a pinion on said shaft, and a spring actuated sector engaging said pinion.
2. A shuttle comprising a base-piece on which the bobbin is mounted, an arch mounted, on said base-piece and embracing the bobbin, convex guard plates above and below the bobbin, and a detachable plate mounted on the upper guard plate and carrying the take-up and tensioning devices.
3. A shuttle comprising a base-piece on

which the bobbin is mounted, an arch 60 mounted on said base-piece and embracing the bobbin, convex guard plates above and below the bobbin, and a detachable bridge-plate of inverted V form carrying the take-up and tensioning devices.

4. A shuttle comprising a base-piece on which the bobbin is mounted, an arch mounted on said base-piece and embracing the bobbin, convex guard plates above and below the bobbin, a detachable bridge-plate having a thread-opening, and a spring tensioning device, and also a centrally pivoted arm having a plurality of thread-engaging loops, together with an actuating spring for said arm, and thread-engaging means co-operating with said arm to take up the thread in a series of passes between them.

5. In a shuttle a take-up device mounted on a bridge-plate of inverted V form and including two relatively spring-actuated members provided with thread-engaging means between which the thread passes in alternate succession a plurality of times.

6. In a shuttle with an arch, a take-up device mounted on a bridge-plate of inverted 85 V form and including a spring-actuated member adapted to deliver the thread at the apex of the arch and to retract the same until stopped by the bridge-plate.

7. A shuttle having a take-up device including a shaft, a pinion connected thereto, a toothed sector meshing with said pinion, a spring for operating the sector, and an arm connected to said shaft having a plurality of thread-engaging loops.

8. A shuttle having a take-up device comprising a shaft, a pinion connected thereto, a toothed sector meshing with said pinion, a spring for operating the sector, an arm connected to said shaft having a plurality of 100 thread-engaging loops, and a co-operating stationary member between which and the arm connected to said shaft the thread is passed a plurality of times.

9. A shuttle having a take-up device comprising a fixed upright arm having a plurality of loops, a shaft, a pinion connected thereto, a toothed sector meshing with said pinion, a spring for operating the sector, and a rotatable arm connected to said shaft 110 having a plurality of thread-engaging loops and adapted to occupy the same vertical plane with the loops in the fixed upright arm when said rotatable arm is in a vertical position.
